(57) CLAIM

I claim the ornamental design for an upright rod for a standing umbrella, as shown and described.

DESCRIPTION

FIG. 1 is a side elevation view of an upright rod for a standing umbrella showing my new design;

FIG. 2 is an enlarged perspective view of the break portion of FIG. 1;

FIG. 3 is a front elevation view of the break portion of FIG. 1;

FIG. 4 is a rear elevation view thereof;

FIG. 5 is a right side elevation view thereof;

FIG. 6 is a left side elevation view thereof;

FIG. 7 is a top plan view of FIG. 2; and,

FIG. 8 is a bottom plan view of FIG. 2.
